UNITED STATES PATENT OFFICE.

CHARLES WAKEFIELD CROWELL, OF SALISBURY, NORTH CAROLINA.

STEAM BOILER.

Original application filed June 19, 1920, Serial No. 390,270. Divided and this application filed March 1, 1921, Serial No. 448,863.

My invention relates to an improvement in steam boilers, this application being a division of my application, Serial No. 390,270, filed June 19, 1920, and the invention 5 consists in the novel construction and arrangement of parts whereby there is produced an open bottom water tube fire box with fire tubes extending from the fire box in such a way as to result in a gain in heating area 10 of the boiler and flues. Other advantages will be apparent from the inspection of the following description and the accompanying drawings in which

Fig. 1 is a longitudinal sectional view of a 15 boiler embodying my invention,

Figure 2 is a half section of the right half of the boiler taken on line 2—2 of Figure 1,

Figure 3 is a left half section taken on the line 3—3 of Figure 1.

Figure 4 is a right half section taken on the line 4—4 of Figure 1.

Figure 5 is a left half section taken on the line 5—5 of Figure 1.

Referring to the drawings, it will be seen 25 that I have provided a boiler having a fire-box A having a suitable grate N and a bridge wall M, a smoke box B in advance of the fire-box, a water section 11 in advance of the smoke box B and a superheater section F.

The fire-box A comprises the cylindrical shell 45 having at its front end the tube sheet 22 and at its rear end the tube sheet 43 and the rear head 12. The water tubes 48 extend the full length of the fire-box between the 35 tube sheets 22 and 43, said water tubes 48 being arranged in concentric circles, having centers coincident with the center of the tube sheet 22, and also being arranged in radial lines from the center of said concentric circles. Opposite each water tube there is 40 provided in the back head 12 a hand hole 18, only one of such holes being shown at the center line K—K on Fig. 1 for the sake of clearness, whereby admission is gained for 45 working on the tubes 48.

Surrounding the fire-box shell 45 and spaced therefrom, as clearly shown by the drawings, is the boiler shell 9 having the tube sheet 21 at its front end and the head 47 at 50 its rear end suitably connected to the back head 12 of the fire-box shell 45. Extending between tube sheets 21 and 22 are the fire-tubes 19. The boiler shell 9 and the fire-box shell 45 have each an opening in their bottoms for the reception of the grate N and the mud frame 46 is secured at the front end

of the grate between the shells 9 and 45, as shown by Figs. 1 and 2. The fire tubes extend from the top of the fire-box shell 45 to a point below the grate N and on a line 60 with the top of the mud frame 46. For access to the water tubes 48, the hand holes 17, only one of which is shown for the sake of clearness, are provided in the tube sheet 21, as shown by Fig. 1. Holes 14 are provided 65 in the fire-box shell 45 to permit the circulation of water from the boiler shell to the space between the tube sheet 43 and the back head 12. Shells 9 and 45 are held together by stays 39, tube sheet 43 and back head 12 70 are held together by stays 15, and tube sheets 21 and 22 are held together by the fire tubes 19 and the stays 20.

The cylindrical form of the boiler shell 9 and the fire-box shell 45 permits the extension of the fire-box beyond the mud frame and at the same time provide for an open bottom fire-box and increases the heating area of the fire-box and the water tubes 48. Also, 75 because of the cylindrical form of the boiler and fire-box shells, the space formerly occupied by a water leg is made use of in a more advantageous way to increase the heating area of the boiler by having fire tubes 80 occupy the space formerly taken up by the water leg extension below the shell as will be clearly apparent to one skilled in the boiler art. And it will further be apparent that in my construction the size of the boiler and fire-box shells may be increased downward from the center line K—K to the point 85 to which the water legs extend in the water leg types of boilers. The fire-box may be as long as is found desirable and may extend beyond the mud frame 46 any suitable distance and thus provision may be made for a 90 larger grate area than would otherwise be advantageously possible.

The fire tubes extending between the fire box and the smoke box have been shown 100 rather short but it will readily be understood that they may be of any desired length, the tubes having been shown of short length because of the limited space available for the drawings and also for the purpose of 105 showing how admission to the front end of the water tubes could be gained in case it were desired to use short tubes. In a construction having a greater distance between the fire and smoke boxes, the hand hole plates 110 in the smoke box would be unnecessary because the water tubes are circularly and

radially aligned, as shown more clearly by Fig. 3, and it thus becomes possible for a man to go inside of the boiler, get on top of the fire tubes and have ample room to work 5 on the front ends of the water tubes, without removing any stays, as he can find room between the stays.

In the construction so far described, the 10 flames and gases pass from the grate N and circulate between the water tubes 48, passing over the bridge wall M and then through the fire tubes 19 into the smoke box B from which they may exit through the stack C when superheated steam is not desired.

15 The above construction may be embodied with boilers having two smoke boxes, each having a smoke stack, with a superheater section located between them and in this 20 connection reference is made to Fig. 1 of the drawings where this construction is shown. The superheater section F is located between the smoke box B and the smoke box K in advance of the superheater section as 25 shown. The superheater section F is cylindrical like the boiler and fire-box shells and is connected to the smoke box B by the connection head 40, as shown by Fig. 1, which is shown as a reduction head but it is obvious that the cylinder 10 of the superheater could be made the same size as the 30 boiler shell, if it were found expedient so to do, without interfering with the principles upon which my invention is based. By making use of the connection head 40, it is possible to make the superheater section cylindrical as described and thereby obviate unnecessary expensive construction. The 35 superheater F is provided with a water section 11 and fire tubes which extend between the smoke boxes, as shown.

40 When the superheater is in operation, the stack C is closed by any suitable damper C' and the gases and other products of combustion pass through the superheater and into 45 the smoke box in advance thereof and thence into the atmosphere, as will be readily understood.

45 From the foregoing description, it will be seen that I have provided a steam boiler 50 which has inner and outer shells of cylindrical form and spaced apart, the inner shell, comprising a fire-box shell, having a flue sheet in its forward end with heating tubes extending therefrom in two directions, one 55 set of tubes being fire tubes and the other set being water tubes and by extending the fire-box beyond the mud frame and occupying the space formerly taken up by a water leg by the fire tubes extending from the tube 60 sheet a gain in heating area has been made, besides the gain made possible by the extension of the fire-box, as has hereinbefore been described. The boiler thus presented is one that is readily and comparatively 65 inexpensively constructed, operated and kept

in repair and is adapted for high pressures and quick steaming, and is economical in fuel consumption.

Having now described my invention, what I claim and desire to secure by Letters Pat- 70 ent of the United States is:

1. In combination, a boiler comprising an outer cylindrical shell having an opening in the rear portion of its bottom for the reception of a grate, a mud frame surrounding 75 said opening, a tube sheet closing the front end of said shell, a smoke box and stack in advance of said tube sheet, a back head and filling rim closing the rear end of said shell, the rim having an opening therein for the reception of the rear end of a fire box, of a cylindrical fire box of less diameter than the boiler shell and disposed with its longitudinal axis below the longitudinal axis of the boiler shell, said fire box having an opening 80 in the rear portion of its bottom for the reception of a grate, the edges of said opening resting on and being secured to the top of the mud frame, a tube sheet in the forward end of the fire box shell spaced from the mud frame, fire tubes extending between said tube sheet and the tube sheet of the boiler shell and disposed below the center of the rear tube sheet, a back head in the rear end of said fire box shell and with the back head of the boiler shell forming a water wall at the rear end of the fire box shell, and water tubes 85 extending through the upper portion of the fire box shell and secured at their forward ends in the forward tube sheet of the fire box 90 and at their rear ends being secured in the rear head of the fire box and communicating 95 with said rear water wall.

2. In combination, a boiler comprising an outer cylindrical shell having an opening in the rear portion of its bottom for the reception of a grate, a mud frame surrounding 100 said opening, a tube sheet closing the front end of said shell, a smoke box and stack in advance of said tube sheet and a back head 105 and filling rim closing the rear end of said shell, the rim having an opening therein for the reception of the rear end of a fire box, of a cylindrical fire box of less diameter than the boiler shell and disposed with 110 its longitudinal axis below the longitudinal axis of the boiler shell, said fire box having an opening in the rear portion of its bottom for the reception of a grate, the edges of said opening resting on and being secured to the top of the mud frame, a tube sheet in the forward end of the fire box shell spaced from the mud frame, fire tubes extending 115 between said tube sheet and the tube sheet of the boiler shell and disposed below the center of the rear tube sheet, a back head in the rear end of said fire box shell and with the back head of the boiler shell forming a water wall at the rear end of the fire box shell, and water tubes 120 extending through 125 the upper portion of the fire box shell and secured at their forward ends in the forward tube sheet of the fire box and at their rear ends being secured in the rear head of the fire box and communicating 130 with said rear water wall.

the upper portion of the fire box shell and secured at their forward ends in the forward tube sheet of the fire box and at their rear ends being secured in the rear head of the fire box and communicating with said water wall, said water tubes being disposed in circular and radial alignment from a center coincident with the axial center of the fire box.

3. In combination, a boiler comprising an outer cylindrical shell having an opening in the rear portion of its bottom for the reception of a grate, a mud frame surrounding said opening, a tube sheet closing the front end of said shell, a smoke box and stack in advance of said tube sheet, a back head and filling rim closing the rear end of said shell, the rim having an opening therein for the reception of the rear end of a fire box, of a cylindrical fire box of less diameter than the boiler shell and disposed with its longitudinal axis below the longitudinal axis of the boiler shell, said fire box having an opening in the rear portion of its bottom for the reception of a grate, the edges of said opening resting on and being secured to the top of the mud frame, a tube sheet in the forward end of the fire box shell spaced from the mud frame, fire tubes extending between said tube sheet and the tube sheet of the boiler shell and disposed below the center of the rear tube sheet, a back head in the rear end of said fire box shell and with the back head of the boiler shell forming a water wall at the rear end of the fire box shell, and water tubes extending through the upper portion of the fire box shell and secured at their forward ends in the forward tube sheet of the fire box and at their rear ends being secured in the rear head of the fire box and communicating with said water wall, said water tubes being disposed in circular and radial alignment from a center coincident with the axial center of the fire box, and a group of stays extending from the front tube sheet of the fire box to the front tube sheet of the boiler and arranged in circular and radial alignment from the axial center of the tube sheet.
4. A cylindrical boiler, a cylindrical fire box therein having its longitudinal central axis disposed below the longitudinal central axis of the boiler, a head closing one end of the boiler, a tube sheet at the opposite end thereof and forming one wall of a smoke box disposed in advance of the boiler, the bottom of the boiler and fire box, adjacent one end, being cut away to provide a grate opening, a mud frame around said grate opening and attached to the edges of the opening in the fire box and boiler whereby the bottom of the fire box is on a level with the top of the mud frame, a bridge wall extending up from the bottom of the fire box and intermediate the ends thereof, water tubes extending longi-

itudinally through the fire box and through the tube sheets thereof and disposed in the upper portion of the fire box, and fire tubes extending through the front tube sheets of the boiler and fire box respectively and communicating with the smoke box and fire box respectively and disposed in the lower portion of the fire box.

5. The combination with a boiler comprising an outer cylindrical shell having its forward end enclosed by a tube sheet, which also forms the rear wall of a smoke box having a stack therein, the rear end of said shell being closed by a back head and filling rim which has an opening therein for the reception or withdrawal of an inner cylindrical shell which forms one wall of a fire box, the rear end of which is enclosed by two heads forming a water wall, holes being provided in the inner shell for the circulation of water between the heads, the front end of the inner shell being closed by a tube sheet, and having fire tubes and stays extending forward therefrom to the first named tube sheet, the inner and outer shells being spaced apart and having a portion of their bottoms removed for a grate opening, a grate in said opening, and a mud frame secured between said shells around the edges of said opening, said inner shell being of uniform diameter throughout its length and having its longitudinal axial center extending below the longitudinal axial center of said outer shell and smoke box.

6. The combination with a boiler comprising an outer cylindrical shell having its forward end enclosed by a tube sheet, which also forms the rear wall of a smoke box having a stack therein, the rear end of said shell being enclosed by a back head and a filling rim which has an opening therein for the reception or withdrawal of an inner cylindrical shell which forms one wall of a fire box, the rear end of which is closed by two heads forming a water wall, holes being provided in the inner shell for the circulation of water between the heads, the front end of the inner shell being closed by a tube sheet and having fire tubes and stays extending forward therefrom to the first named tube sheet, the inner and outer shells being spaced apart and having a portion of their bottoms removed for a grate opening, a grate in said opening, and a mud frame secured between said shells around the edges of said opening, said inner shell being uniform in diameter for its entire length and having its longitudinal axial center extending below the longitudinal axial center of said outer shell and said smoke box, said inner shell resting on said mud frame and being extended forward its full diameter a distance from said grate opening, water tubes extending through said inner shell above and around each side of the longi-

tudinal axial center of said boiler shell arranged in circular and radial alignment and secured at their front ends to the tube sheet of the inner shell, and at their rear ends to the inner head of said rear water wall.

7. The combination with a boiler comprising an outer cylindrical shell having its forward end closed by a tube sheet, which also forms the rear wall of a smoke box having a stack therein, the rear end of said shell being enclosed by a back head and a filling rim which has an opening therein for the reception or withdrawal of an inner cylindrical shell which forms one wall of a fire box, the rear end of which is enclosed by two heads forming a water wall, holes being provided in the inner shell for the circulation of water between the heads, the front end of the inner shell being closed by a tube sheet, and having fire tubes and stays extending forward therefrom to the first named tube sheet, the inner and outer shells being spaced apart and having a portion of their bottoms removed for a grate opening, a grate in said opening, and a mud frame secured between said shells around the edges of said opening, said inner shell being uniform in diameter for entire length and having its longitudinal axial center extended below the longitudinal axial center of said outer shell and said smoke box, said inner shell resting on said mud frame and being extended forward its full diameter a distance from said grate opening, said fire tubes extending from the longitudinal axial center of the boiler and smoke box downward to the bottom of the tube sheet of the fire box, stays

extending between said tube sheets and secured thereto in alignment above said fire tubes, connection head means being provided in said smoke box for connecting a cylindrical shell superheater of less diameter than said boiler shell and of different diameters at different elevations, said superheater shell having three tube sheets spaced apart therein, fire tubes extending through and secured thereto forming a water wall between the superheating section and said smoke box, and said fire tubes communicating with said smoke box and another smoke box having a discharge stack in advance of said superheater.

8. The combination with a boiler having an ordinary smoke box and stack at its forward end, an ordinary boiler shell and open bottom fire box at its rear end, a grate in said opening, a second smoke box and stack between the first mentioned smoke box and the fire box, fire tubes extending between said second smoke box and the fire box, of a cylindrical shell superheater of less diameter than said boiler shell and having three tube sheets spaced apart therein, and fire tubes extending through and secured to each of said tube sheets, forming a superheating section in the forward end of said shell and a water wall in the rear end thereof, said superheater extending between and forming a wall of each of said smoke boxes, and connection head means being provided in said second smoke box for connecting said front smoke box and superheater sections of various smaller diameters than said boiler shell or at different elevations.

CHARLES WAKEFIELD CROWELL.
